UNITED STATES PATENT OFFICE.

CLARENCE WHEELER JONES, OF NORWALK, CONNECTICUT.

MAGAZINE-BRUSH.

1,134,865.

Specification of Letters Patent. Patented Apr. 6, 1915.

Application filed April 17, 1914. Serial No. 832,597.

To all whom it may concern:

Be it known that I, CLARENCE WHEELER JONES, a citizen of the United States, residing at Norwalk, in the county of Fairfield and State of Connecticut, have invented certain new and useful Improvements in Magazine-Brushes, of which the following is a specification.

This invention comprehends certain new and useful improvements in magazine brushes and has for its primary object to provide a device of this character which will be constructed in such manner that it will be of extremely simple construction and operation, as well as highly efficient in use.

Another object is to provide a device of this character which will be constructed as a tooth brush, shaving brush, blacking brush and the like, and which may be provided with means for automatically closing the discharge opening of the barrel.

A further object of this invention is to provide a device of this character in which will be included a follower and means for retaining the follower in engagement with the material to be automatically discharged from said barrel.

A still further object of this invention is to provide a device of this character which will be of improved construction and operation and which will be formed in such manner that the brush proper may be readily detached from the barrel or connected with the latter.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a longitudinal section through the complete device, Fig. 2 is a detail transverse section taken on the plane of line 2—2 of Fig. 1, and Fig. 3 is a detail transverse section through the brush proper on the plane of line 3—3 of Fig. 1.

Referring in detail to the drawings by numerals, 1 designates the barrel of the device which has one end open and adapted to be closed by a screw cap 2, having a

flanged outer end 3 for engagement against the end of the barrel to limit inward movement of said cap. Secured to the cap 2 is one end of a helical expansive spring 4, 60 which has its opposite end engaged in the follower 5 positioned in said barrel and bearing against the paste or other material 6 to be forced through the valve opening 7 of the reciprocating valve 8 within the discharge end of the barrel and through the aligned passages 9 and 10 to the bristles 11 of the brush proper 12, by way of the turned end 13 of said passage 10.

It will be understood that the passage 10 70 extends longitudinally of the brush proper and when the reduced threaded inner end 14 of said brush proper 12 is engaged in the interiorly threaded socket 15 at the forward end of the barrel 1. It will therefore 75 be seen that as the passage 9 extends from a main portion or the hollow portion of the barrel 1 to the socket 15, the passage 10 will connect with the passage 9 when the brush proper 12 is secured to the barrel 1.

The reciprocating valve 8 is in the form of a plate having the central valve opening 7, previously mentioned, extending transversely therethrough and said valve 8 is positioned against the front wall 16 of the 85 main or hollow portion of the barrel 1 and is resiliently retained in its uppermost position by means of the leaf spring 17 which has one end secured against the outer face of the barrel 1, while its offset free end is 90 engaged against the underface of the head 18 of the stem 19, which extends through the guide opening 20 in the upper face of the barrel 1 and has its lower or inner extremity secured to the upper end of the 95 valve 8. It will therefore be seen that the valve 8 is guided in its reciprocating movement caused by pressing the head 18 of the stem 19 toward the barrel 1 to bring the valve opening 7 opposite the passage 9 and 100 thereby permit the follower 5 to force the paste or other material 6 through the valve opening 7 and passages 9 and 10 to the brush

bristles 11, it being understood that as soon as the pressure upon the head 18 is released, the 105 springs 17 will serve to automatically return the stem 19 and valve 8 to normal position. To assure proper movement of the valve 8, I have provided a guide pin 21 in the bottom of the barrel 1 and extending 110 upwardly therein beneath the valve 8 and projecting into the socket 22 formed in the

bottom of said valve 8, and it will be readily apparent that this guide pin 21, together with the stem 19, will prevent lateral movement of the valve 8 and assure proper operation of the same.

While I have shown and described the preferred embodiment of my invention, it will be understood that minor changes in the details of construction, combination and arrangement of parts may be made without departing from the spirit and scope of the invention as claimed or sacrificing any of the advantages thereof.

What is claimed is:—

15 A magazine tooth brush of the class described comprising a barrel having a longitudinal bore with a reduced portion forming a stop wall at one end of said large portion of said bore, a reciprocating valve en-

gaged against the said stop wall and having 20 a transverse opening adapted to register with the smaller portion of said longitudinal bore, a stem engaging the upper portion of said valve and extending through the guide opening in the upper face of said barrel, a guide pin in the bottom of the barrel and extending upwardly and projecting into the socket formed in said valve, a leaf spring having one end secured against the outer face of said barrel, and the opposite end engaging the head of the stem above said barrel.

In testimony whereof I affix my signature in presence of two witnesses.

CLARENCE WHEELER JONES.
